UNITED STATES PATENT OFFICE.

HARRY M. KORETZKY, OF NEW YORK, N. Y.

ELECTRIC FLASH-LIGHT.

1,198,239.

Specification of Letters Patent. Patented Sept. 12, 1916.

Application filed November 27, 1915. Serial No. 63,729.

To all whom it may concern:

Be it known that I, HARRY M. KORETZKY, a citizen of the United States, and a resident of the city of New York, borough of the Bronx, in the county of the Bronx and State of New York, have invented a new and Improved Electric Flash-Light, of which the following is a full, clear, and exact description.

10 This invention relates to pocket flashlights of that type disclosed in United States Letters Patent No. 1,155,249 granted to me on the 28th day of September, 1915, wherein the flashlight comprises a watch-like casing in which is located a rectangular battery having oppositely disposed contacts at its sides which are adapted to engage respectively an electric lamp and a pushbutton contact, the pushbutton contact and one 15 terminal of the lamp being grounded on the casing so that when the pushbutton is pressed to engage the contact or terminal of the battery, the circuit of the lamp will be completed.

20 The invention has for its general objects to improve the construction of flashlights of the character referred to so as to be reliable and efficient in use, comparatively simple and inexpensive to manufacture, and 25 so designed that the circuit can be kept closed indefinitely by the locking of the pushbutton in closed circuit position.

More specific objects of the invention are the provision of improved means for supporting the socket in which the lamp screws, such means forming a stop for holding the battery in proper position; and also the provision of a novel form of switch button which, by the pressing of the button, will 30 close the circuit, and by the turning of the button will lock the circuit closed.

With such objects in view, and others which will appear as the description proceeds, the invention comprises various novel 35 features of construction and arrangement of parts which will be set forth with particularity in the following description and claims appended hereto.

In the accompanying drawing, which 40 illustrates one embodiment of the invention and wherein similar characters of reference indicate corresponding parts in all the views, Figure 1 is a plan view of the flashlight with the cover removed and the pushbutton switch in open circuit position; Fig. 45 55 2 is a similar view with the circuit closed;

Fig. 3 is a sectional view on the line 3—3, Fig. 2; Fig. 4 is a perspective view of the battery; Fig. 5 is a perspective view of the lamp-holding socket and the battery stop; 60 and Fig. 6 is a perspective view of the contact or stem of the pushbutton.

Referring to the drawing, 1 and 2 designate the two halves of the casing which are divisible on the dotted line 3, Fig. 3. This casing is preferably circular, like a watch, and positioned therein is a rectangular battery 4. This battery is of similar construction to that shown in the patent hereinbefore referred to, and at one side it has a 65 spring terminal or contact 5, and at the opposite side the paper insulating covering is removed at 6 to expose a portion of the battery at 7 to form the other terminal of the battery. The terminal 7 is adapted to be engaged by a contact 8 which is formed on the inner end of a pushbutton stem 9 that is slidably mounted in a barrel 10 rigidly fastened to the section 2 of the casing. Rigidly fastened to the outer end of the stem is 70 a button or head 11. In the barrel is a spring 12 which is adapted to hold the contact 8 in open circuit position, as shown in Fig. 1. Attached to the barrel is a ring 13 which serves as a grip or means for attaching the flashlight to a chain. Obviously, by 75 pressing inwardly on the pushbutton the contact 8 engages the terminal 7 of the battery and thereby the circuit of the lamp will be completed. To enable the lamp to be held in a closed circuit, the pushbutton stem 9 has a cross bar 14 forming oppositely extending lugs. These lugs engage in recesses 15 in a collar 16 fastened in the section 2 of the casing. These recesses 15 provide 80 lugs 17, with the inner surfaces of which the cross bar 14 is engageable by pressing the pushbutton inwardly and then giving it a quarter turn, whereby the contact 8 will be held in the closed circuit position shown in Fig. 2. For only momentarily closing the 85 circuit it is merely necessary to press the pushbutton inwardly so that the contact 8 will engage the terminal 7 of the battery. 90

In the casing at the side opposite from the pushbutton switch is the lamp 18, which is set into a socket 19 disposed in the periphery of the casing. The socket has a threaded portion into which the lamp screws, and it also has a reflector 20. The 95 threaded shell 21 of the lamp is grounded on the metallic socket 19, and this in turn is 100 110

grounded on the casing of the flashlight. The central contact 22 of the lamp engages the spring contact 5 of the battery. The socket 19 is brazed or otherwise secured in a bracket 23 which is a strip of metal formed into a base 24 which is brazed or otherwise fastened to the section 2 of the casing, and extending upwardly from the base is an apertured member 25 in which the lamp 10 socket 19 is fastened, and at the opposite end of the base 24 is an upstanding flange 26 which is adapted to be engaged by the battery so as to form a stop therefor, whereby the battery is held in proper position.

15 From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown 20 is merely illustrative and that such changes may be made when desired as fall within the scope of the appended claims.

Having thus described my invention, I claim as new and desire to secure by Letters 25 Patent:

1. A flashlight comprising a casing, a battery arranged within the casing and having terminals, a lamp mounted in the casing and having one terminal connected with one 30 terminal of the battery and the other terminal grounded on the casing, a barrel on the casing extending outwardly therefrom, a stem slidable in the barrel and projecting into the casing to form a contact for engaging the other terminal of the battery from that engaged by the lamp, a ring attached only to the barrel, a pushbutton connected with the outer end of the stem for moving the stem longitudinally and rotatably, said pushbutton being adapted to be 35 pressed inwardly, said ring being adapted to be held while the pushbutton is being pressed inwardly, and interlocking means arranged within the casing and disposed 40 respectively on the stem and on the casing for locking the stem in closed circuit position by an inward and rotary movement of the stem.

2. In a flashlight of the class described, 45 the combination of a circular casing, a rectangular battery mounted therein and having terminals disposed at diametrically opposite points, one of the terminals being a yielding spring, a pushbutton arranged in the casing and forming a contact for one terminal of the battery, a lamp disposed in the casing at the opposite side from the pushbutton and having one of its terminals en-

gaging the other terminal of the battery, a bracket arranged in the casing to form a support for the lamp, and a stop engaging the battery for holding the same in place and withstanding the thrust on the battery produced by the pushbutton.

3. In a flashlight, the combination of a 70 casing, a battery therein, a lamp connected with one terminal of the battery, a pushbutton stem engageable with the other terminal of the battery, a guide in which the stem is longitudinally and rotatably movable, a pushbutton on the outer end of the stem, a spring acting to hold the stem in open circuit position, a lug on the portion of the stem disposed within the casing, and a fixed abutment within the casing with 75 which the lug is engageable when the stem is pressed inwardly to thereby lock the stem in closed circuit position.

4. In a pocket flashlight, the combination of a casing, a battery therein, a switch in the 80 casing having a movable element engageable with one terminal of the battery and grounded on the casing, a lamp having one terminal engageable with the other terminal of the battery, a socket in which the lamp 85 is mounted, and a bracket in which the socket is secured and which is fastened to the casing to ground the socket thereon, said bracket consisting of a piece of metal having a base portion fastened to the casing and an upstanding apertured member in which the socket is fastened, and an upstanding flange forming a stop with which the battery engages.

5. In a flashlight, the combination of a 100 casing having an opening at one side, a pushbutton switch at the opposite side, a battery between the switch and said opening, a bracket fastened in the casing and having an upstanding member provided with an 105 opening registering with the opening in the casing, and forming a stop for the battery at the side opposite from the pushbutton, a combined lamp socket and reflector fastened in the opening in the upstanding member 110 and extending into the casing through the opening thereof, a lamp threaded in the socket and having one terminal grounded thereon and grounded through the bracket on the casing, a terminal on the battery arranged to be engaged by the lamp, and a terminal on the battery arranged to be engaged by the switch.

In testimony whereof I have signed my name to this specification in the presence of 120 two subscribing witnesses.
